UNITED STATES PATENT OFFICE.

JOSEPH R. BLAINE, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

SHEET-REGISTERING MECHANISM.

1,300,563.

Specification of Letters Patent. Patented Apr. 15, 1919.

Application filed June 23, 1916. Serial No. 105,324.

To all whom it may concern:

Be it known that I, JOSEPH R. BLAINE, a citizen of the United States, residing at Oak Park, in the county of Cook and State 5 of Illinois, have invented certain new and useful Improvements in Sheet-Registering Mechanism, of which the following is a specification.

With few exceptions, it has been customary heretofore to feed the sheets individually 10 to a printing press against substantially stationary gages or guides, so that during the travel of the paper it is necessarily stopped in its movement, at least momentarily, to 15 secure the desired registration. In such cases the inertia of the paper must be instantly overcome when the grippers of the impression cylinder, which are constantly traveling at full speed, grasp the sheet and 20 transfer it to the cylinder. As will be appreciated, in a structure of that character the gages and grippers must operate with great precision to secure registration of the sheet and its transfer or clamping to the 25 rapidly traveling impression cylinder. In other words, when a sheet of paper is gaged and gripped in a press of this kind the stationary sheet has instantaneously imparted to it the full speed of travel of the impression cylinder periphery, which renders accurate 30 registration difficult if not impossible. Moreover, an instant before the grippers close, the guides must get out of the way, leaving the sheet uncontrolled during this 35 instant, affording a further chance for error in getting accurate register.

The present invention has for its primary object the provision of means for securing accurate front and side registration of sheets 40 fed to a printing couple, without stopping the sheet in its forward movement and at substantially the speed of the sheet taking grippers and the impression cylinder, whereby the full speed capacity of the press 45 is utilized without its being limited in any way by the necessary registering process, while the correct registry of the sheet is in no way impaired by the speed of sheet travel.

50 This object is accomplished according to my invention by providing a rotary sheet registering mechanism including gages traveling at the same speed as the grippers on the impression cylinder and also including elec-

trically operated means for frictionally seizing the front of the sheet at the point of delivery by the sheet feeder approximately adjacent the front gage and advancing the sheet to the said gage; also for similarly engaging the side of the sheet and drawing 60 it laterally to a side gage traveling with the sheet; and thereafter releasing the sheet an instant after the same has been taken by the grippers on the impression cylinder,—the sheet registering mechanism and the grippers traveling in arcs approaching a point at which the path of the sheet is tangent to each whereby the front gage moves in its orbit into the path of the sheet as fed, and after the sheet is registered and is seized by 70 the grippers of the impression cylinder moves out of the sheet path to enable the sheet to pass on with the impression cylinder without interruption or interference.

In order that a complete understanding 75 of the invention and more or less of the details of construction of a preferred embodiment of the invention may be fully understood, I have illustrated in a more or less fragmentary and diagrammatic manner one 80 desirable embodiment of the invention in the accompanying drawings, which form a part of this specification, and to which reference should be made. It is clear, however, that the invention may be embodied in other 85 and varied constructional forms without departure from the essence thereof, wherefore the drawing and description are to be taken in an illustrative rather than in an unnecessarily limiting sense. 90

Figure 1 is a detail view in front elevation of the mechanism for imparting front register;

Fig. 2 is a similar view in side elevation of the parts shown in Fig. 1; 95

Fig. 3 is a view similar to Fig. 1 but illustrating the mechanism for imparting side register; and

Fig. 4 is a view similar to Fig. 2 showing the mechanism for imparting side register 100 in side elevation.

Front register.

Having reference to the drawings (Figs. 1, and 2) the impression cylinder is indicated at 13 provided with its grippers 14, while adjacent and in parallel relation thereto is suitably mounted in the frame of 105

the press a shaft 15 driven at a speed corresponding with that of the shaft of the impression cylinder.

An arm 16 is keyed upon the shaft 15 by 5 means of an extended boss 16^a whereon is loosely mounted a collar 17 held stationary by means of an arm 18 which takes over the fixed rod 19 extending between the side frames of the press. The stationary collar 10 17 bears cams 20 and 21, the purpose of which will hereinafter appear.

Loosely mounted upon said boss 16^a of the arm 16 is a gage arm 22 carrying the front gage 23 and having projecting therefrom 15 lugs 24, 25 to the former of which is fulcrumed by the pivot 26 an angle lever 27, 28, while the lug 25 serves as a mounting for a swivel block 29 screw threaded for engagement by a screw 30 mounted within a 20 similar swivel block 31 and having a milled head 32. Fulcrumed on the gage arm 22 by the pivot 33 is an angle lever 34, 35. The arm 28 of the first mentioned angle lever carries a roller 36 adapted to travel on the 25 cam 20 while the arm 34 of the other angle lever carries a roller 37 adapted to travel on the cam 21.

To the arm 27 of the first angle lever is connected by means of a pin 38 and a slot 30 39 an arcuate shoe 40 extending laterally from another arm 41 which is likewise loosely mounted upon the boss 16^a. To the extreme front end of the shoe 40 is pivoted at 42 by means of a link 43 and a second 35 pivot 44 the lower end 45 of a rod 46 which latter is pivoted at 48 in the outer end of the arm 35 of the second angle lever. The link 43 has projecting beyond its pivot 42 a flipper 49, the purpose of which will herein- 40 after be made clear. A spring 50 serves to hold the roller 36 against its cam while a similar spring 51 serves the same purpose with reference to the roller 37.

It should be understood that the shaft 15 45 extends the full width of the press and that a counterpart of the mechanism above described is mounted upon the said shaft 15 and the rod 19 near the two sides of the press, that is to say separated a distance slightly 50 less than the width of the paper to be fed, so that a front gage is provided for effecting register of the sheets at the front edge and adjacent each side. The bosses 16^a are slidable longitudinally upon the shaft 15 so 55 as to properly position the two registering mechanisms in order to act upon the sheet at the proper point. The position of each having been determined, the arm 16 is clamped upon the shaft 15 in an obvious 60 manner. The knurled head 32 of the screw 30 is then manipulated in order to position the gage arms 22 of the two mechanisms in exact transverse alinement and in position longitudinally to effect the proper front 65 register of the sheet.

Mounted upon the stationary collar 17 of each registering mechanism is an arm 52 carrying contact blades 53, 54, connected by the leads 53^a, 54^a with the poles of a battery, not shown, which blades are arranged 70 to be wiped over by the brushes 55, 56 mounted on the revolving arm 22, the said brushes being connected by means of leads 55^a, 56^a with the electromagnet 57 disposed immediately to the rear of the front gage 75 and flush with the lower face of the shoe 40.

The press being in motion, the gage arm 22 revolves and carries with it the front gage 23 at a peripheral speed corresponding exactly to that of the grippers upon the 80 impression cylinder by reason of its being tied to the arm 16 by means of the screw 30. The angle levers 27, 28, and 35, 36 likewise revolve with the arm 22, being fulcrumed thereto respectively at 26 and 33. 85

As the sheet 58 is fed to the press its front edge comes against the front gages 23 or approximately in that position, usually within a sixteenth to a quarter of an inch therefrom. The roller 37 riding upon the 90 cam 21 acts through the lever 34, 35 upon the link 43 and the flipper 49 whereby the latter is approximately closed upon the forward end of the sheet 54, the slot at 43^a, within which the pivot 44 acts, providing 95 for a sufficient amount of lost motion to prevent any gripping of the sheet by the flipper. At this moment, the brushes 55, 56 having reached the contact blades 53, 54, and the magnet 57 being energized, the latter acts on the flipper 49 as an armature pulling the same up against the lower face of the sheet and thus frictionally gripping the same between the flipper and the lower face of the shoe 40, the degree of said pressure being regulable by the strength of the current. 105

Immediately thereafter the roller 36 riding upon the cam 20 moves the angle lever 27, 28 thereby advancing the shoe 40 and the flipper 49 with the magnet 57 relatively to the gage 23, the gage traveling at the speed of the grippers and the shoe 40 at a slightly greater speed by reason of the action of the lever. The sheet thus gripped at 110 its forward edge between the flipper 49 and the shoe 40 is likewise advanced until it comes in contact with the gage 23 whereupon meeting with this obstruction the sheet conforms to the speed of the gage while the 115 shoe 40 continues to move at a faster speed. The front gage 23 continues its movement at the speed of the grippers on the impression cylinder, the sheet being held against the shoe 40 and abutting the gage 23 by the 120 flipper 49 until the grippers on the impression cylinder have gripped the forward end of the sheet. This transfer takes place on the tangent point of the shoe 40 with the impression cylinder 13 so that the flipper 49 125 130

and the grippers 14 can both be acting on the sheet at the tangent point, and in fact an instant later. During the next one-eighth inch travel of the cylinder beyond the 5 tangent point, the shoe 40 has moved the flipper forward out from under the sheet so that the latter is left free to continue its path on the impression cylinder. The roller 37 then clears the high part of cam 21 and 10 the flipper 49 is opened by the action of the spring 51 and is then ready to receive the next sheet as it comes into position. Similarly roller 36 clears the high part of cam 20 and spring 50 restores the lever to its 15 original position with the shoe 40 retracted as indicated, ready for the next cycle.

Side register.

Upon the shaft 15 outside the two mechanisms for effecting front register of the sheet 20 as above described, is a similar organization of mechanism for effecting side register of the sheet (Figs. 3 and 4). Herein the side gage arm 60 is keyed to the shaft 15 by means of 25 an extended boss 60^a, and a similar collar 17^a is loosely mounted upon the boss 60^a and held in stationary position by means of the arm 18^a embracing as before the shaft 19. This collar is provided with a cam 61 in 30 one plane and another cam 62 in a different plane. The side gage arm 60 carries the side gage 64, the position of which is adjustable transversely of the press and longitudinally of the shaft 15 by means of the 35 adjusting screw 65 journaled in the collar 66 clamped to the shaft 15, and threaded in the lug 67 on the boss 60^a, the screw being operable by means of its knurled head for positioning of the gage 64, after which the 40 arm 60 is clamped in position upon the shaft by means of the clamp screw 68.

Transversely slidable within the gage arm 60 is a shoe 69 carrying a roller 70 which works within an oblique slot 71 of an 45 angle lever 72, 73, the opposite arm of which lever has a roller 74 arranged to travel upon the cam 61. The other end of the shoe 69 opposite the roller 70 has pivoted thereto at 75 an arm 76 connected by means of a rod 77 with a link 78 pivoted at 79 to the shoe 69, which link 78 is extended to form a flipper 80. A coil spring 81 holds the stop 82 of the arm 76 against shoe 69. The angle lever 72, 73 is fulcrumed to the gage arm 60 upon 50 a pivot 85, and similarly pivoted to said arm at 86 is an angle lever 87, 88, the arm 88 of which is provided with a roller 89 arranged to ride upon the cam 62, while the opposite arm 87 of said lever has an offset portion 55 provided with an inclined face 90 adapted to engage the arm 76 whereby to open and close the flipper 80.

Mounted on the stationary collar 17^a is an arm 91 carrying contact blades 92, 93 connected by leads 92^a, 93^a with the poles of

a battery, not shown, which blades are arranged to be wiped over by the brushes 94, 95, mounted on the revolving arm 60, the said brushes being connected by leads 94^a, 95^a with the electromagnet 96 disposed immediately adjacent the side gage 64 and flush with the lower face of the shoe 69. 70

In use the flipper 80 is normally approximately closed, being held in this position by the tension of the spring 81. As the sheet 75 is approached approximately to the gage 23 for front register as previously described the cam roller 89 rides upon the cam 62 opening the flipper 80 to allow the side edge of the sheet to pass and to offer no hindrance 80 to the action of the front register. Front register having been obtained the roller 89 rides off the cam 62 closing the flipper 80 loosely upon the sheet 58 at the side thereof. The pivotal connection between the rod 77 85 and the link 78 is such as to provide sufficient lost motion to prevent any gripping of the sheet by the flipper 80, but substantially at the moment of the closing of the flipper, the brushes 94, 95 having reached 90 the contact blades 92, 93, the magnet 96 is energized and acts on the flipper 80 as an armature pulling the same up against the lower face of the sheet and frictionally gripping the sheet between the flipper and 95 the lower face of the shoe 69, the degree of friction being slightly greater than that of the front register flippers.

Shortly thereafter the roller 74 rides upon the cam 61 bringing the oblique slot 100 71 to bear through the roller 70 upon the shoe 69, drawing the sheet 58 to the left, as shown in Fig. 3, against the side gage 64, the flipper sliding upon the sheet during the further lateral movement of the flipper 105 and shoe after the side registration of the sheet.

At the moment the grippers close on the sheet, the flipper 80 still has hold of the sheet and during the next one-eighth inch of 110 travel of the cylinder, the flipper draws out from under the sheet and allows it to pass freely with the impression cylinder. The flipper then remains open, the magnet being deenergized, until the next cycle starts. 115 After the sheet is taken the roller 74 rides off of high part of cam 61 bringing the shoe 69 back to its starting position.

I claim:

1. The combination of means for imparting front register to a sheet fed to a printing couple having grippers without interrupting the forward movement of the sheet, comprising a front gage mounted to revolve at the speed of the grippers in a curved path 120 into and out of the sheet path, a revoluble sheet clamping device traveling normally with the gage, means to actuate the clamping device to seize the sheet, and means to temporarily accelerate the speed of the 125 sheet 130

clamping device to advance the sheet to the gage, the clamping device comprising a shoe movable toward and from the gage and a flipper hinged to the forward end of the shoe, and electro-magnetic means to press the flipper upon the sheet to hold the latter against the shoe.

2. The combination of means for imparting front register to a sheet fed to a printing couple having grippers without interrupting the forward movement of the sheet, comprising a front gage mounted to revolve at the speed of the grippers in a curved path into and out of the sheet path, a revoluble sheet clamping device traveling normally with the gage, means to actuate the clamping device to seize the sheet, and means to temporarily accelerate the speed of the clamping device to advance the sheet to the gage,
- 10 the clamping device comprising a shoe movable toward and from the gage and a flipper hinged to the forward end of the shoe, mechanical means to approximately close the flipper, and electro-magnetic means to press the flipper upon the sheet to hold the latter against the shoe.
- 15
- 20
- 25

3. The combination of means for imparting front register to a sheet fed to a printing couple having grippers without interrupting the forward movement of the sheet, comprising a front gage mounted to revolve at the speed of the grippers in a curved path into and out of the sheet path, a revoluble sheet clamping device traveling normally 30 with the gage, means to actuate the clamping device to seize the sheet, and means to temporarily accelerate the speed of the clamping device to advance the sheet to the gage, the clamping device comprising a shoe 35 movable toward and from the gage and a flipper hinged to the forward end of the shoe, mechanical means to approximately close the flipper, and electro-magnetic means to press the flipper upon the sheet to 40 hold the latter against the shoe, the electro-magnetic means comprising a magnet traveling with the shoe, a normally open electric circuit therefor, and circuit-closing means 45 arranged to be actuated by the revolving mechanism immediately after the closing of the flipper. 50

the upper.

4. The combination of means for imparting front register to a sheet fed to a printing couple having grippers without interrupting the forward movement of the sheet, comprising a front gage mounted to revolve at the speed of the grippers in a curved path into and out of the sheet path, a revoluble sheet clamping device traveling normally with the gage, means to actuate the clamping device to seize the sheet, and means to temporarily accelerate the speed of the clamping device to advance the sheet to the gage, the clamping device comprising a shoe movable toward and from the gage.

55

5. The combination of means for imparting front register to a sheet fed to a printing couple having grippers without interrupting the forward movement of the sheet, comprising a front gage mounted to revolve at the speed of the grippers in a curved path into and out of the sheet path, a revoluble sheet clamping device traveling normally with the gage, means to actuate the clamping device to seize the sheet, and means to temporarily accelerate the speed of the clamping device to advance the sheet to the gage, the clamping device comprising a shoe movable toward and from the gage.

60

6. The combination of means for imparting front register to a sheet fed to a printing couple having grippers without interrupting the forward movement of the sheet, comprising a front gage mounted to revolve at the speed of the grippers in a curved path into and out of the sheet path, a revoluble sheet clamping device traveling normally with the gage, means to actuate the clamping device to seize the sheet, and means to temporarily accelerate the speed of the clamping device to advance the sheet to the gage, the clamping device comprising a shoe movable toward and from the gage.

65

and a flipper hinged to the forward end of the shoe, mechanical means to approximately close the flipper, and electro-magnetic means to press the flipper upon the sheet to hold the latter against the shoe, the electro-magnetic means comprising a magnet traveling with the shoe, a normally open electric circuit therefor, and a circuit-closing means arranged to be actuated by the revolving mechanism immediately after the closing of the flipper and including stationary contacts and revolving brushes arranged to wipe over said contacts. 70 75 75

5. The combination of means for imparting front register to a sheet fed to a printing couple having grippers without interrupting the forward movement of the sheet, and means for imparting side register to said sheet comprising a side gage mounted to revolve at the speed of the grippers in a curved path to which the plane of the sheet path is tangent, a revoluble sheet clamping device traveling with the gage, means to actuate the clamping device to seize the side of the sheet, and means to move the clamping device laterally to bring the side of the sheet to the gage, the sheet clamping device comprising a shoe and electro-magnetic means to frictionally press the sheet against the shoe. 95 90

against the shoe. 6. The combination of means for imparting front and side register to a sheet fed to a printing couple having grippers without interrupting the forward movement of the sheet, comprising front gages mounted to revolve at the speed of the grippers in a curved path into and out of the sheet path, a side gage mounted to revolve at the speed of the grippers in a curved path to which the plane of the sheet path is tangent, revoluble sheet clamping devices traveling with the front and side gages, means to actuate the clamping devices to seize the sheet, means to temporarily accelerate the speed of the clamping devices of the front registering mechanism to advance the sheet to the gage, and means to shift the clamping devices of the side registering mechanism laterally to bring the sheet against the side gage, the sheet clamping devices comprising shoes revolvably mounted to move in an orbit corresponding substantially to those of the gages and also in said orbit toward and from the gages, a flipper hinged to the forward end of the shoe, and electro-magnetic means to press the flipper upon the sheet to hold the latter against the shoe. 100 105 110 115 120

7. The combination of means for imparting front and side register to a sheet fed to a printing couple having grippers without interrupting the forward movement of the sheet, comprising front gages mounted to revolve at the speed of the grippers in a curved path into and out of the sheet path, a side gage mounted to revolve at the speed 125 130

- of the grippers in a curved path to which the plane of the sheet path is tangent, revoluble sheet clamping devices traveling with the front and side gages, means to actuate 5 the clamping devices to seize the sheet, means to temporarily accelerate the speed of the clamping devices of the front registering mechanism to advance the sheet to the gage, and means to shift the clamping devices of 10 the side registering mechanism laterally to bring the sheet against the side gage, the sheet clamping devices comprising shoes revolubly mounted to move in an orbit corresponding substantially to those of the gages 15 and also in said orbit toward and from the gages, a flipper hinged to the forward end of each shoe, mechanical means to approximately close the flipper, and electro-magnetic means to press the flipper upon the sheet to 20 hold the latter against the shoe.
8. The combination of means for imparting front and side register to a sheet fed to a printing couple having grippers without interrupting the forward movement of the 25 sheet, comprising front gages mounted to revolve at the speed of the grippers in a curved path into and out of the sheet path, a side gage mounted to revolve at the speed of the grippers in a curved path to which the plane of the sheet path is tangent, revoluble sheet clamping devices traveling with the front and side gages, means to actuate 30 the clamping devices to seize the sheet, means to temporarily accelerate the speed of the clamping devices of the front registering mechanism to advance the sheet to the gage, and means to shift the clamping devices of 35 the side registering mechanism laterally to bring the sheet against the side gage, the sheet clamping devices comprising shoes revolubly mounted to move in an orbit corresponding substantially to those of the gages and also in said orbit toward and from the gages, a flipper hinged to the forward end of the shoe, and electro-magnetic means to press the flipper upon the sheet to 40 hold the latter against the shoe, the electro-magnetic means comprising a magnet traveling with the shoe, a normally open electric circuit therefor, and circuit-closing means arranged to be actuated by the revolving mechanism immediately after the closing of the flipper and including stationary contacts 45 and revolving brushes arranged to wipe over said contacts.
- In witness whereof I have hereunto signed by name in the presence of two subscribing witnesses.
